UNITED STATES PATENT OFFICE.

WILLIAM C. CLAUSEN, OF WAUWATOSA, WISCONSIN, ASSIGNOR TO MILWAUKEE STAMPING CO., OF WEST ALLIS, WISCONSIN, A CORPORATION OF WISCONSIN.

BAG FRAME.

Application filed March 21, 1921. Serial No. 454,003.

To all whom it may concern:

Be it known that I, WILLIAM C. CLAUSEN, a citizen of the United States, and resident of Wauwatosa, in the county of Milwaukee and State of Wisconsin, have invented new and useful Improvements in Bag Frames, of which the following is a description, reference being had to the accompanying drawings, which are a part of this specification.

10 This invention relates to improvements in bag frames.

Frames for travelling bags are usually constructed of commercial strip metal bent into U-shape members, of angular shape in

15 cross section, which are hinged together at their ends to form the mouth of the completed bag. The outer member carries the lock and the inner member carries the hasp parts which are engaged by the lock when

20 the parts are in closed position. The lock is usually riveted to a medial portion of the inner part of the lock side of the frame and occupies a considerable transverse portion of the upper flange of said part. The upper

25 flange portion of the inner or hasp member of the frame, when in closed position, extends closely within or beneath the upper flange portion of the lock member of the frame and to permit this it is necessary to

30 recess or cut away a considerable portion of the upper flange of the inner member to accommodate the lock. As a result, bag frames, as now ordinarily constructed, are structurally weak at this point and are

35 easily bent out of shape or broken.

It is one of the objects of the present invention to overcome this objectionable feature and provide a bag frame in which the recessed portion of the frame is reenforced

40 in a manner to greatly strengthen the weak portion without materially increasing the weight of the parts or interfering with the mounting of the frame in the bag of which it forms a part.

45 A further object of the invention is to provide a bag frame in which a thicker and more firm backing is provided for riveting the hasp member thereto, which will prevent the riveted ends from pulling through the frame part when subjected to excessive strain in use.

50 A further object of the invention is to provide a bag frame which is of simple and

inexpensive construction, is strong and durable and is well adapted for the purpose described.

With the above and other objects in view, the invention consists of the improved bag frame and its parts and combinations as set forth in the claims and all equivalents thereof.

In the accompanying drawing in which the same parts in all of the views are indicated by the same reference characters:

Figure 1 is a side view of the improved bag frame shown in partly open position;

Figure 2 is a transverse sectional perspective view thereof taken on a larger scale;

Figure 3 is a similar view of a modified form of reinforcing member; and

Figure 4 is a similar view of another modification.

Referring to the drawing, the numeral 8 indicates the U-shaped outer or lock member and 9 the U-shaped inner or hasp member of the improved bag frame which are hinged together in overlapping relation at the ends by pivot pins 10 to form the opening of the bag. The frame members are 80 formed of strip metal and are of angular or L-shape in cross section to form upper outer flange portions 11 and 12, and lower inner flange portions 11' and 12' to which the bag parts are connected in the usual manner 85 well known in the art. The upper flange part 11 is formed with an opening 13 for receiving the key-hole portion of the lock (not shown) and the edge portion of the upper flange 12 is cut away or recessed as 90 indicated by the numeral 14 to accommodate the lock before mentioned. This cutting away or recess 14 materially weakens the frame member and a reinforcing member

15 of L-shape in cross section is mounted 95 on the outer side of the flange portion 12' with the flange part 15' extending outwardly from its lower edge portion. The reinforcing member 15, in the preferred form, is secured to the flange 12' by rivets 16, 100 some of which extend through and fasten the hasp 17 to the inner side of the flange 12'.

As thus constructed, the reinforcing flange 15' extends outwardly to reenforce the cut away portion of the flange 12 with 105 out in any manner interfering with the

bag portion (not shown) which is attached to the bag frame above the reenforcing member.

In the modified form shown in Figure 3, 5 the reenforcing flange 18 forms part of and extends outwardly from the lower edge portion of the hasp 17, and in the modified form shown in Figure 4, the reenforcing flange 19 is integral with the frame member 9 and extends outwardly from the lower edge portion thereof.

From the foregoing description, it will be seen that the reenforcing means for the bag frame is of very simple construction and is 15 well adapted for the purpose described.

What I claim as my invention is:

1. A bag frame, comprising a lock member, a hasp member connected thereto and having a recessed edge portion, and means 20 angular in cross section for reenforcing said recessed edge portion.
2. A bag frame, comprising a lock member, a hasp member hinged thereto and having a recessed edge portion, and an outwardly extending means for reenforcing said edge portion, said outwardly extending means extending downwardly and outwardly below the plane of the recessed edge portion.
3. A bag frame, comprising a lock member, a hasp member hinged thereto and having an inwardly extending recessed portion and a downwardly extending portion, and a reenforcing means extending outwardly 35 from the lower part of the downwardly extending portion.
4. A bag frame, comprising a lock member of angular form in cross section, a hasp member of angular form in cross section 40 and having a recess formed in its upper inner edge, the end portions of both members being hinged together, and a reenforce-

ing member connected to and extending outwardly from the lower portion of the hasp member.

5. A bag frame, comprising a U-shaped lock member of angular form in cross section, a U-shaped hasp member of angular form in cross section and having its end portions hinged to the end portions of the 50 lock member, the inner upper edge portion of the hasp member having a recess, and an angular reenforcing member mounted on the hasp member and having a flange extending outwardly from its lower portion.

6. A bag frame, comprising an outer U-shaped lock member of angular form in cross section, a U-shaped hasp member having its end portions hinged to the end portions of the lock member, said hasp member being of 60 angular form in cross section, and an elongated strip of material of angular form in cross section having one portion rigidly secured to the outer side of the hasp member and another portion extending outwardly 65 from the lower edge part of the hasp member.

7. A bag frame, comprising an outer U-shaped lock member of angular form in cross section, an inner U-shaped hasp member having its end portions hinged to the end portions of the lock member, said lock member overlapping the hasp member when in closed position and said hasp member having an upper inner recessed edge, and an 70 elongated strip of material of L-shape in cross section having one side portion rigidly connected to a side portion of the hasp member and its other side portion extending outwardly from the lower edge part of the 75 hasp member.

In testimony whereof, I affix my signature.

WILLIAM C. CLAUSEN.
